UNITED STATES PATENT OFFICE

2,597,984

MEANS FOR FIXING HOLLOW RIVETS
AND THE LIKE

Jean Gobin dit Daudé, Neuilly-sur-Seine, France

Application February 25, 1948, Serial No. 10,816
In France February 28, 1939Section 1, Public Law 690, August 8, 1946
Patent expires February 28, 1959

4 Claims. (Cl. 218—15)

1

In order to fix a hollow rivet or similar article by means of two opposite riveting tools the said hollow rivet is generally presented threaded on a spindle which is slidably mounted in one of the two riveting tools and which projects from the tool under the action of a spring or other non-positive connection between said spindle and said tool, and the tool and spindle and the opposite tool are brought together, the movement towards one another continuing until the rivet is driven home.

However, towards the end of this relative approaching movement the end of the spindle which is made to project as stated above is subjected to an impact due to the opposite tool or due to an accessory of said tool and this shock in time causes the spindle to be twisted or even broken, especially if its diameter is small and if its end is tapered as is frequently the case. The greater the resistance opposed by the spring or the like to the motion of the sliding spindle the more the consequences of the impact are to be feared. Now in the case of a vertical machine comprising an upper distributor and a spindle mounted slidably in the upper tool (this being the most frequent type) the above mentioned resistance must be great enough to ensure a proper jamming of said spindle in the hollow rivet during the feed, as will be explained hereinafter. In the case of a rivet closed at the end to be riveted, the impact is transmitted to the end of the spindle through the rivet; in the case of a rivet open at the end to be riveted there is direct contact between the end of the spindle and the opposite tool or an accessory of the said tool.

The process according to the invention entirely avoids the above-mentioned disadvantages. It consists in that a bringing together of said corresponding tool and spindle on the one hand and the opposite tool on the other hand is first effected and then a relative movement between the corresponding tool and the spindle is effected as soon as the end of the latter comes within a small distance of the opposite tool or of any accessory of said tool, said relative movement being such that said end of the spindle is protected from any shock due to the opposite tool or due to any accessory of said tool while the bringing together of said two tools is completed for driving home the rivet, the completion of the bringing together controlling said relative movement.

More particularly in the case of an eyelet or a tubular rivet open at the end to be riveted the above-mentioned relative movement is such that

2

all contact between the end of the spindle and the opposite tool or any part of said tool is avoided.

In the latter case it is preferable to adjust the relative movement between the spindle on which said eyelet or rivet is threaded and the corresponding tool so that the end of the spindle is still partly engaged in the eyelet or rivet at the moment when the penetration of the end of the opposite tool or of an accessory part of the latter should take place in the hollow of the eyelet or tubular rivet. The correct penetration or engagement of the end, projection or the like in the hollow of the eyelet or tubular rivet is thus ensured. Otherwise this correct engagement would not take place or if it did take place the eyelet or rivet would no longer be centered by the spindle and there would still be a danger of the resulting riveting being defective.

According to one construction of an automatic machine for carrying out the process defined above the relative movement between the spindle and the corresponding tool is caused by a fixed stop which at an opportune moment makes contact with a shoulder on said spindle or a part secured to the latter. This stop is preferably mounted adjustably on the frame.

According to a second construction, the relative movement between the spindle and the corresponding tool is caused by a movable stop, the movement of the stop being controlled by the movement of the opposite tool.

An elastic friction device can be mounted on the tool so as to press on a flat portion formed longitudinally in the spindle so that the relative movement between the spindle and the corresponding tool takes place under the action of a relatively considerable force. More particularly this force should be greater than the force necessary to ensure proper jamming of the spindle in the rivet presented by the distributor at the time of feeding. For this purpose the elasticity of this device is preferably adjustable.

With the friction device, the machine also comprises a device intended to act during the movement of the two riveting tools away from one another after the rivet has been pressed home and intended to cause the spindle to slide relatively to the corresponding tool so as to cause said spindle to project from said tool so that it can again be fed by the distributor.

The accompanying drawings show purely descriptive and non-limitative examples of two constructions according to the present invention. The drawings do not show the whole of the machine which can be of any type but only the two

3

opposite riveting tools and the corresponding tool carriers, the assembly being arranged according to the invention.

In the drawings:

Figs. 1 and 2 are sectional side views of one construction;

Figs. 3 and 4 are sectional side views of another construction.

It is to be noted that in the Figures 1 and 3 the arrows show the directions of movement which the parts in question have when they move from the positions in which they are shown.

The machine shown in Figs. 1 and 2 comprises a lower tool 1 mounted in a fixed tool carrier 1a and an upper tool 2 mounted in a movable tubular tool carrier 2a. A spindle 3 slides in the upper movable tool 2 and its tapered end 4 projects from said tool when the spindle occupies the position shown in Fig. 1.

The spindle 3 is fixed to a spindle carrier 3a which slides in the tool carrier 2a and which is provided with a flat portion 5 formed longitudinally and bounded by two shoulders 6 and 7. Two fixed stops 8 and 9 passing through a longitudinal hole 10 provided in the upper tool carrier 2a co-operate with the two shoulders 6 and 7 as explained below. The stops 8 and 9 are fixed to the frame 30 by means of the head 12 of the screw 11. The position of the stops 8 and 9 can be regulated by the screw 11 and for this purpose are provided with elongated holes 13 and 14 through which said screw 11 is engaged.

The spindle carrier 3a comprises a second flat portion 15 formed longitudinally. A pin 16 slides at right-angles to the flat portion 15 in a tubular cylindrical part 17 which is fixed to the tool carrier 2a by means of screws 18. The end of the cylindrical part 17 is closed by a screw-threaded plug 23 on which bears a helical spring 19. The spring 19 presses the pin 16 against the flat portion 15 through a hole 16a formed in the tool carrier 2a. The pressure can be adjusted by screwing or unscrewing the plug 23.

The end 4 of the spindle 3 co-operates with a movable distributor 20 (Fig. 1) which carries tubular rivets such as 21. The work to be riveted is shown at 22 (Fig. 2).

In order to simplify the explanations it will be assumed that the cycle of operation of the machine begins when the upper tool 2 is at the top of its stroke as shown in Fig. 1. The stop 9 is then in contact with the shoulder 7 of the spindle carrier 3a and the end 4 of the spindle 3 projects from the tool 2 by a distance a . The distributor 20 is in the feeding position and the rivet 21 which is the first to be presented by the distributor lies in alignment with the spindle 3a at a small distance from the tapered end 4 of said spindle.

The different operations of the working cycle of the machine are therefore as follows: The upper tool 2 and its tool carrier 2a descend towards the fixed lower tool 1 carrying with them in their movement the spindle 3 owing to the pressure of the pin 16. The tapered end 4 of the spindle 3 then enters the tubular rivet 21 and the pressure of the pin 16 on the flat portion 15 of the spindle carrier 3a is such that no sliding of the said spindle in the corresponding tool 2 takes place before the end of the said spindle is sufficiently engaged in the rivet 21 to prevent the escape of the latter during subsequent operations. The upper tool 2 continues to descend and as soon as the end 4 of the spindle 3 has become engaged in the rivet 21 the spindle 3 can

4

no longer follow the upper tool 2 in its movement as it is prevented from further descent by the distributor 20 and the rivet 21 carried by the latter. The upper tool 2 and the tool carrier 2a therefore slide past the spindle carrier 3a and the spindle 3 and the end 4 of said spindle 3 does not project from the upper tool 2 more than a small distance which is less than a when the engaged rivet 21 leaves the distributor 20 as a result of the withdrawal of the latter. The tool 2 then carries the spindle 3 with it towards the fixed tool 1.

During the subsequent downward movement of the upper tool 2 and the spindle 3 a time comes when the shoulder 6 of the spindle carrier 3a makes contact with the stop 8, thus stopping the downward movement of the spindle 3. At this precise moment the end 4 of the said spindle projects from the tool 2 by the same distance as during the withdrawal of the distributor 20.

The distance between the tapered end 4 of the spindle 3 and the point 25 of the lower tool 1 is then very small and less than the length of the rivet 21. This distance, however is not negligible.

The upper tool 2 continues to move downwards while the spindle 3 is kept stationary by the stop 8. The lower end 24 of the said tool makes contact with the head of the rivet 21 and carries said rivet along, the rivet 21 covering the point 25 of the fixed tool 1. As the distance between the spindle 3 and the point 25 remains constant after the said spindle has been stopped, and as this distance is smaller than the length of the rivet 21, this rivet is guided by the end 4 of the spindle 3 until the engagement thereof with the point 25 is obtained. The maximum pressure on the rivet is then exerted (Fig. 2) and riveting is completed without any contact between the tapered end 4 of the spindle 3 and the point 25 of the fixed tool 1.

The upper tool 2 and its tool carrier 2a then begin to move upwards away from the lower fixed tool 1. The spindle 3 is carried along with them until the shoulder 7 of the spindle carrier 3a makes contact with the stop 9. The upper tool 2 continues to move upwards until it reaches the upper limit of its stroke and the distributor 20 returns into the feeding position. After this the tapered end 4 of the spindle 3 projects from the corresponding tool 2 by a distance a . All the parts of the machine have now returned to the positions shown in Figure 1.

The relative movement between the spindle of the upper tool and the tool itself in the machine shown in Figs. 3 and 4 which is a machine for fixing two-piece rivets, is effected by means of a movable stop and the movement of this stop is controlled by the movement of the opposite tool which in this case is movable.

For this purpose the lever 79 is pivotally mounted at 80 on the frame 81 of the machine. The end 82 of said lever co-operates with the shoulder 84 which limits at the upper part the flat portion 85 formed longitudinally in the spindle carrier 68a which is rigid with the spindle 68. The latter slides in the upper tool 52 which is fixed at the end of the tool carrier 52a. This sliding movement is braked as in the previous machine by the friction pin 86 which is pressed by a spring 87 against the flat longitudinal portion 88 of a second recess 89 provided in the spindle carrier 68a.

The other end 90 of the lever 79 is pivoted on one end of a connecting rod 91 of adjustable

5

length, the other end of which is pivoted on one end 82 of a lever 93 which is pivotally mounted on a pin 94 secured to the frame 81 of the machine. The other end 95 of the lever 93 is made rigid with the upward and downward movements of the lower tool carrier 72a on which the lower tool 72 is fixed.

This device is completed by the fixed stop 96 the position of which is adjustable for the purpose of co-operating with the shoulder 83 which limits the flat portion 85 at its lower part.

In the position (Figure 3) in which the two opposite tools 52 and 72 have the maximum separation the end 97 of the spindle 68 projects a long way from the tool 52 owing to the stop 96 which by its action on the shoulder 83 of the spindle carrier 68a has caused the latter and the spindle 68 to slide relatively to the tool 52 during the last stage of the upward movement of the said tool.

The distributor 98 is in the feeding position and the rivet element 99 presented first by the distributor lies in the extension of the spindle 68 and of its tapered end 97.

The tapered end 100 of the pin 101 which is slidably mounted in the lower movable tool 72 also projects from the said tool. The corresponding distributor 102 is in the feeding position and the other rivet element 103 presented first by the distributor lies in the extension of the pin 101 and of its end 100.

From this position the upper tool 52 and lower tool 72 move towards one another and the ends 97 and 100 of the spindle 68 and pin 101 enter the rivet elements 99 and 103 respectively. During this time said rivet elements 99 and 103 are borne respectively by the upper and lower distributors 98 and 102. The ends 97 and 100 of spindle 68 and pin 101 are thus stopped in engagement with the rivet elements, whereas the tools continue their movement toward one another sliding past these ends in such a manner that these ends 97 and 100 retract slowly in relation to the tools 52 and 72. The upper and lower distributors 98 and 102 are withdrawn a few moments after ends 97 and 100 have penetrated into the rivet elements 99 and 103. Preferably, the machine will be stopped immediately after the above-described operations.

The previously pierced work 104 is then engaged in any known manner on the rivet element 99 which is stationary on the spindle 97. The tool carriers 52a and 72a again move towards one another and the shoulder 84 of the spindle carrier 68a makes a contact with the stop 82 which prevents any subsequent movement of the spindle carrier by the corresponding tool carrier 52a. The pin 101, the pin carrier 101a of which co-operates with an arrangement of stops 105, 106, similar to that provided for the spindle carrier 3a of the machine described above, is also prevented by the said arrangement of stops from further following the upward movement of the tool carrier 72a and tool 72. When the stops 82 and 105 have both acted respectively on the spindle carrier 68a and on the pin carrier 101a the small distance between the end 97 of the spindle 68 and the end 100 of the pin 101 is less than the length of the rivet element 99 but never becomes zero.

In effect, as the lower tool 72 and upper tool 52 continue to move towards one another for pressing the rivet, the lever 79, driven by the rod 91 and the lever 93, continues to pivot about the fixed point 80. Its end 82 which is in contact

6

with the shoulder 84 of the spindle carrier 68a raises the latter as well as the spindle 68 and causes the complete withdrawal of its end 97 within the tool 52 without said spindle having made any contact with the lower tool 72 or with the end 100 of the corresponding pin 101. The maximum pressure of the rivet then takes place (Fig. 4).

The tools then move away from one another with their tool carriers which carry with them the spindle carrier 68a and spindle 68 on the one hand and the pin carrier 101a and pin 101 on the other hand, respectively, until the shoulder 83 of said spindle carrier makes contact with the fixed stop 96 and interrupts the upward movement of the spindle 68 causing its end 97 to project from the tool 52. The pin carrier 101a is likewise stopped by the stop 106 which has the effect of causing the end 100 of the pin 101 to project from the lower tool 72. The end 97 of the spindle 68 and the end 100 of the pin 101 are then sufficiently spaced from one another to permit the free passage of the distributors 98 and 102 which move to their feeding positions.

During this time the upper tool 52 and lower tool 72 continue to move away from one another which has the effect of increasing the projection of the end 97 of the spindle and the end 100 of the pin from the said tools until the latter reach the outer limits of their strokes. All the parts of the machine have returned to the position which they occupy in Fig. 3.

It can be seen that with the process and apparatus according to the invention the spindles, mandrels or pins are no longer subjected to any shock and can therefore be made as thin or as tapered as desired. Thus in some cases it may be advantageous to form these parts from piano strings suitably fixed in a suitable support.

It is likewise obvious that the work need not be previously pierced if it is sufficiently plastic to be pierced by the penetration of the rivet or by the opposite tool, the latter being provided for this purpose with a pointed end.

In the case in which the latter method of piercing the work is used with a machine adapted for fixing rivets comprising two elements 99 and 103 the tapered end 97 of the spindle 68 co-operating with the element 99 will be sufficiently pointed for the operation, by raising the work 104 during the stoppage of the tools after the feed, to cause the work 104 to be traversed by the said end 97 which in this case functions as the pointed end of the tool.

55. What I claim is:

1. Spindle motion control arrangement in a riveting machine having a fixed frame, a first and a second riveting tool, said riveting tools being in axial alignment on either side of the riveting plane, means for displacing said first tool toward and away from said riveting plane, a spindle mounted axially in said first tool and means for feeding a rivet into the spindle path for threading said rivet over said spindle when said spindle is moved toward said riveting plane, said spindle being provided according to this spindle motion control arrangement with a shoulder portion and mounted for sliding frictional axial motion in and in relation to said first riveting tool so as to be driven thereby when no resistance is met by said spindle in its driven movement and held against motion when said driven movement is opposed, whereby said first riveting tool will continue its movement alone and thus slide axially along said spindle, said

spindle control arrangement comprising an adjustable stop member fast with said fixed frame, said shoulder portion of said spindle abutting against said adjustable stop member during the movement of said first riveting tool toward said riveting plane so as to hold said spindle against motion at a predetermined stop-point while said first riveting tool will complete its movement toward said riveting plane and approach to said second riveting tool, thus performing the riveting step proper, said predetermined spindle stop-point being placed at will in relation to the riveting plane by adjusting said adjustable stop member.

2. Spindle motion control arrangement in a riveting machine having a fixed frame, a first and a second riveting tool, said riveting tools being in axial alignment on either side of the riveting plane, means for moving said tools toward and away from said riveting plane, a first spindle mounted axially in said first tool, a second spindle mounted axially in said second tool and means for feeding the elements of a two-element rivet into the paths of said spindles toward said riveting plane, said first and second spindles in the spindle motion control arrangement being both provided with a shoulder portion and mounted for sliding frictional axial motion in and in relation to said first and second riveting tools respectively, each of said spindles being thus driven in the movement of its related riveting tool, in which it is axially mounted, when no resistance is encountered by the spindle in its driven movement, and each of said spindles being held against motion when this driven movement is opposed so as to allow the tool in which each spindle is axially mounted to slide axially along said spindle, this spindle motion control arrangement comprising a movable stop member, means actuated by the movement of said second tool for controlling the displacement of said movable stop member, said first spindle abutting with its shoulder portion against said movable stop member in the movement of said first riveting tool toward said riveting plane and being held against motion at a predetermined stop-point, and a fixed stop member, said second spindle abutting with its shoulder portion against said fixed stop member in the movement of said second riveting tool toward said riveting plane and being held against motion at a predetermined stop-point, whereby said riveting tools will complete their movements toward said riveting plane during the stopping of said spindles and approach each other in order to perform the riveting step proper.

3. A spindle motion control arrangement for riveting machine having a fixed frame, a first and a second riveting tool, both tools being in axial alignment on either side of a riveting plane, means for moving said tools toward and away from said riveting plane, a spindle mounted coaxially in said first riveting tool and means for feeding a rivet into the path of said spindle for threading said rivet over said spindle when the latter is moving toward said riveting plane, said spindle in said spindle motion control arrangement being formed with a flat surface and a shoulder portion and mounted for axial sliding movement in and in relation to said first tool, and said spindle motion control arrangement comprising a small cylinder mounted for sliding motion in said first tool transversely thereto, a spring member mounted in said first tool and urg-

ing said cylinder against said flat surface in said spindle, and an adjustable stop member fast with said fixed frame, said shoulder portion of said spindle abutting against said adjustable stop member during the movement of said first tool toward said riveting plane and being held against motion at a predetermined stop-point while said first riveting tool is completing its movement toward said riveting plane by approaching against said second riveting tool to perform the riveting step proper, said predetermined stop-point of said spindle being selected as desired in relation to the riveting plane by adjusting said adjustable stop member.

4. A spindle motion control arrangement for riveting machine having a fixed frame, a first and a second riveting tool, both tools being in axial alignment on either side of a riveting plane, means for displacing said first and second tool toward and away from said riveting plane, a first spindle mounted coaxially in said first riveting tool, a second spindle mounted coaxially in said second riveting tool, means for feeding the elements of a two-element rivet into the paths of said spindles for threadedly engaging said elements over said spindles when said spindles are moved towards said riveting plane, said first and second spindles, according to said spindle motion control arrangement, being both provided with a flat surface and a shoulder portion and mounted for axial sliding movement in and in relation to said first and second riveting tools respectively, said spindle motion control arrangement comprising a first small cylinder mounted for sliding motion in and in relation to said first tool transversely thereto, a spring member mounted in said first tool and adapted to urge said first small cylinder against said flat surface of said first spindle, a movable stop member, means actuated by the movement of said second tool for controlling the displacement of said movable stop member, said first spindle abutting with its shoulder portion against said movable stop member when said first tool is moved toward said riveting plane and being thus held against motion at a predetermined stop-point, and a fixed stop member, said second spindle abutting with its shoulder portion against said fixed stop member when said second tool is moved toward said riveting plane and being thus held against motion in a predetermined stop-point, whereby said riveting tools will complete their movements toward said riveting plane during the stopping of said spindles and approach each other in order to perform the riveting step proper.
